(57) **CLAIM**

The ornamental design for a pool post support as shown and described.

DESCRIPTION

FIG. 1 is a front perspective view of a pool post support showing our new design.

FIG. 2 is a right-side elevation view of the pool post support of FIG. 1, the left-side elevation view being a mirror image thereof.

FIG. 3 is a rear elevation view of the pool post support of FIG. 1.

FIG. 4 is a front elevation view of the pool post support of FIG. 1.

FIG. 5 is a top plan view of the pool post support of FIG. 1; and,

FIG. 6 is a bottom view of the pool post support of FIG. 1. The dot-dash-dot broken lines shown in the drawings depict portions of the pool post support that form no part of the claimed design.

1 Claim, 5 Drawing Sheets
